UNITED STATES PATENT OFFICE.

SAMUEL H. TINSMAN, OF FORT MADISON, IOWA.

PLOW.

No. 894,169.

Specification of Letters Patent.

Patented July 21, 1908.

Application filed April 18, 1906. Serial No. 312,351.

To all whom it may concern:

Be it known that I, SAMUEL H. TINSMAN, a citizen of the United States of America, and resident of Fort Madison, Lee county, 5 Iowa, have invented a certain new and useful Improvement in Plows, of which the following is a specification.

My invention relates to improvements in plows of the wheeled or sulky type, and has 10 for its object, generally stated, the provision of a simple and durable construction, in combination with certain novel details, thereby to increase the general efficiency of the plow; and a special object of my invention 15 is to provide an improved foot-lift, whereby a wide range is given to the vertical movements of the plow, and the same is easily controlled; and a further object is the provision of a positive locking means, whereby 20 the plow may be positively secured in any required position, and by which the rocking depth of the plow may be varied at will.

These and such other objects as may hereinafter appear are attained by my invention, 25 an embodiment of which is illustrated in the accompanying drawings, in which

Figure 1 is a plan view of my improved plow. Fig. 2 is a side elevation of the same. Fig. 3 is an enlarged detail of a portion of 30 Fig. 2. Fig. 4 is a vertical cross-section on line 4—4 in Fig. 3, looking in the direction indicated by the arrows. Fig. 5 is a horizontal cross-section on line 5—5 of Fig. 4, looking in the direction indicated by the 35 arrows.

Like figures of reference indicate like parts in the several figures of the drawings.

Referring now by figure to the accompanying drawings, 1 represents the plow; 2 the point of the plow; 3 the heel of the plow; 4 the plow beam; 5 the land-side wheel; 6 the furrow-side wheel; and 7 the colter wheel. The frame 8 is mounted on the wheels through the medium of posts 9 and 45 10, and the support 11, which latter support is secured to the bail-shaped axle 12 to which the plow beam 4 is journaled. The furrow side of the axle is journaled to the brace-bar 13 of the frame by an ear 14. 50 The land side of the axle is connected to the land-side wheel through the medium of a crank-bar 15. The seat 16 is secured to the frame by a spring support 17. A connecting bar or bearing 18 unites the bail with 55 the frame, being secured to the frame by a

bolt 19. This bar terminates in the rack 20 secured between the ears 21 of the spring container 22, which latter is secured to the lever 23. A locking bolt 24 is secured to the end of a rod 25 which is operated by the usual bell-crank lever 26 attached to the handle of the lever 23. A spring 26^a is seated in the container 22, by means of which the locking bolt 24 is kept in engagement with the rack 20. A supplemental 60 arm or rack 27 is swingingly secured to the frame, which passes through an eye 28 in a supporting bar or foot lever 29 secured on the axle at 30. The end of the arm 27 is racked, as shown at 31, and a bolt 32 passes 65 through the forks 33 and 34 of the bar 29 and normally engages the rack teeth 31.

Mounted on the arm or foot lever 29 is a short lever 35, preferably fulcrumed on the bolt 32. The bar portion of this lever 35 is 70 turned inwardly at right angles, forming a disengaging bar 36. The lower arm of the lever 35 is turned outwardly at right angles, forming a finger 37 extending under the arm 27 and adapted to engage it and raise the 75 rack out of engagement with the bolt 32. The upper end of the bar or foot lever 29 is formed into a horizontally extending foot-rest 38. The foot-lift 39 is rigidly secured to the end of the axle 12 and provided with a 80 foot-rest 40.

The crank arm 15 is loose on the axle 12, and the lever 39 is adapted to swing above the spindle 41 of the land-side wheel 5. With this arrangement, the hand lever 23 is rigid 90 with the arm 15. In this way the wheel 5 can be controlled by said hand lever while the plow and axle 12 remain locked by the rack 31 relatively to the frame of the plow.

Referring to Fig. 2, the plow is shown in 95 normal position out of the ground. If it is desired to force the plow into the ground, the lever 23 is pushed forward to the end of its throw and locked in position by means of the locking-bolt 24 engaging the ratchet 20. At 100 this time the arm or foot rest 29 is held locked in place by means of the bolt 32 engaging the rack 31. If it is desired to force the plow still deeper into the ground, the operator places his foot on the rest 38 and the toe of 105 his boot on the disengaging bar 36. By pressing down on this bar, the finger 37 is forced against the rack arm 27, throwing it up, and throwing the rack 31 out of engagement with the bolt 32. The operator then kicks for- 110

ward with his foot still on the rest 38, thereby forcing the axle outward and the plow deeper into the ground. By removing the pressure of the toe from the bar 36, the arm falls 5 down and is automatically locked in position by means of the bolt 32 engaging the rack 31. In this way the plow and beam are locked in up and down and intermediate positions relatively to the frame.

10 This device is of great value, as it enables the operator to easily regulate the depth of the furrow.

The foot levers 29 and 39 are both rigid with the axle 12; which latter extends forward in the form of a bail. Said foot lever 15 39 can be pressed down to rock the axle or bail 12 and thereby raise the plow in the frame. The spindle 41 is not rigid with its axle 12, but is movable relatively thereto, for 20 the purpose of manipulating the land-side wheel while the plow and frame are locked together.

While I have shown my improved foot lift in connection with a plow, I do not, for the 25 broader purposes of my invention, limit myself to any particular kind of plow or other implement.

I claim:

1. In a wheeled plow, the combination of a 30 frame, a bail-shaped axle, a hand lever on said axle, a land-side wheel having a spindle rigid with said hand lever, a foot-lever rigid with said axle, and means for engaging said foot-lever to lock the same in the desired position.

2. In a wheeled plow, the combination with a plow and beam, a frame, supporting 40 wheels, an axle secured to said plow beam, a hand lever mounted on said axle, a land-side wheel controlled by said hand lever, a foot lever rigidly secured to said axle, an arm mounted on said frame and provided with a rack portion, and means carried by said foot lever for engaging said rack portion to lock 45 said axle in the desired position.

3. In a wheeled plow, the combination with a plow and beam, a frame, supporting 50 wheels, a bail-shaped axle secured to said plow beam, a hand lever mounted on said axle, a land-side wheel controlled by said hand lever, a foot lever rigidly secured to said axle, an arm mounted on said frame and provided with a rack portion, means carried by said foot lever for engaging said rack portion to lock 55 said axle in the desired position, and means whereby said rack portion may be thrown out of engagement, with the foot lever.

4. In a wheeled plow, the combination 60 with a plow and beam, a frame, supporting wheels, a bail-shaped axle secured to said plow beam, a hand lever mounted on said axle, a land-side wheel controlled by said hand lever, a foot lever rigidly secured to said 65 axle, an arm mounted on said frame and pro-

vided with a rack portion, means carried by said foot lever for engaging said rack portion to lock said axle in the desired position, and means whereby said rack portion may be thrown out of engagement, with the foot lever, comprising an auxiliary lever secured to said foot lever and adapted to throw said rack portion of the arm into and out of locking engagement.

5. A wheeled plow comprising a frame, a plow and means for locking it in up and down and intermediate positions relatively to the frame, a foot lift for said plow, a land-side wheel, a rear caster wheel, a front furrow wheel mounted to skew or swing around, 80 and means for controlling the land-side wheel while the frame and plow are locked together.

6. A wheeled plow comprising a frame, a plow and means including a foot controlled 85 rack for locking it in up and down and intermediate positions relatively to the frame, and means for raising and lowering the frame and plow while locked together.

7. A wheeled plow comprising an axle, a plow and means for locking it in up and down and intermediate positions, by rotating 90 and holding the axle in different positions, a rearwardly extending foot lever secured to the axle for lifting the plow, a land-side wheel, and means for controlling the land-side wheel while the plow and axle are locked in any position.

8. A wheeled plow comprising a plow and foot operated means for locking it at different 100 depths in the ground, including a pivoted rack bar, and means engaging the rack, as set forth.

9. A wheeled plow comprising a frame, a plow in the frame, and foot operated means 105 for locking the plow to the frame at different depths in the ground, including a rack bar pivoted to the frame, and means engaging the rack, as set forth.

10. A wheeled plow comprising a frame, a plow in the frame, means for positioning the 110 plow at different depths in the ground, front wheels and a rear caster wheel, means for locking the plow to the frame at different depths in the ground, including a bar pivoted 115 to the frame, and a rack and pin connection between the said bar and plow.

11. A wheeled plow comprising a frame, a plow and crank axle, means for rocking said 120 axle to raise and lower the plow relatively to the frame, including two foot levers fixed to the axle, a rack on one of said elements, and means on another of said elements for engaging said rack to lock the plow in up and down and intermediate positions.

12. In a wheeled plow, the combination of a frame, a crank axle, a spindle movably mounted on said axle, a land-side wheel on 125 said spindle, two foot levers secured to said axle, for rocking or rotating the same, a hand 130

lever for moving the spindle on its axle to control the land-side wheel, means for locking the hand lever to the frame, and a rack bar pivoted to the frame and engaging one of said foot levers to lock the plow at different depths in the ground.

13. The combination of a wheeled frame, an implement hung in said frame, a pair of foot levers for raising and lowering said implement, a rack bar pivoted to the frame, and means on one foot lever for engaging the rack to lock the implement up and down and in intermediate positions.

14. The combination with a wheeled implement, of foot operated means for raising and lowering the implement, and means including a swinging rack bar for locking the implement in up and down and intermediate positions.

15. The combination of an implement, means for raising and lowering the same, and means including a swinging rack bar for locking the implement in up and down and intermediate positions.

16. The combination of a wheeled frame, an implement hung in said frame, foot levers for raising and lowering said implement, a rack bar pivoted on the frame, means on one foot lever for engaging the rack, and foot-operated means on the same lever for disen-

gaging the rack bar therefrom when it is desired to change the position of the implement.

17. The combination of an implement, foot-operated means for raising and lowering said implement, a frame, a bar pivoted to the frame at its rear end and extending forward therefrom, and means for engaging the free end of said bar to lock the implement in up and down and intermediate positions.

18. The combination of an implement, a pair of foot levers for raising and lowering said implement, a pivoted bar, a rack and pin connection between said bar and the lever for lowering the implement, and foot-operated means on the same lever for disengaging the bar therefrom when it is desired to change the position of the implement.

19. In an agricultural implement, a locking device comprising a foot lever, a pivoted rack bar, means on said lever for engaging the rack to lock the implement in different positions, and foot-operated means on said lever for disengaging the rack bar therefrom to change the position of the implement.

Signed by me at Chicago this 31st day of March 1906.
